(57) **CLAIM**

The ornamental design for a device for efficient paste dispensing, as shown and described.

DESCRIPTION

FIG. 1 is a perspective drawing of my new design, the lines in phantom illustrating the environment in which the invention is used, that is a tube of toothpaste;

FIG. 2 is a side elevational view of my new design, the opposite side being a mirror image thereof;

FIG. 3 is a top view of my design, the bottom view being a mirror image thereof; and,

FIG. 4 is an end view of my design, the opposite side being a mirror image thereof.

1 Claim, 1 Drawing Sheet

FIG. 1

FIG. 2

FIG. 3

FIG. 4
